ASSIGNORS OF ONE-THIRD TO RALPH D. BROWN, OF SEATTLE, WASHINGTON.

PORTABLE ROADWAY.

1,422,280.

Specification of Letters Patent.

Patented July 11, 1922.

Application filed March 31, 1921. Serial No. 457,167.

To all whom it may concern:

Be it known that we, ARNOLD C. LUETGERT and ERNEST H. MEIKLEJOHN, citizens of the United States of America, and residents of the city of Seattle, in the county of King and State of Washington, have invented certain new and useful Improvements in Portable Roadways, of which the following is a specification.

10 Our invention relates to roadways and particularly to one which may be made in sections to be portable.

The present invention is intended particularly for use in logging operations, which 15 must be carried on in territories devoid of permanent roads for the most part. Such operations frequently require the hauling of a small number of heavy timbers from an isolated area, at times over considerable 20 distances, and frequently over very rough, broken, or muddy ground. It is a considerable expense to prepare good roads into such remote and unsettled country, for their only use is to enable the hauling of the timbers 25 from a restricted area, after which the roads are generally useless. Lacking good roads over which the timbers may be hauled by motor equipment, they must either be cut smaller, to be handled by horses, or they 30 must be brought out by cable apparatus, which is expensive in first cost and in operation, to the great damage of the timber being handled, and the standing timber as well.

35 It is evident that if a road could be made quickly, easily, and inexpensively, without considerable preliminary leveling or other preparation, which would enable the use of heavy motor equipment, and which was 40 made of elements which permit it to conform to the general contour of the surface, and which might be moved about or carried from one place to another, wherever it was needed, it would greatly assist such logging 45 operations. Such a road would also be useful in road building, making fills, and in like situations, and it is our principal object to produce the same.

Another object is to produce a sectional 50 roadway in which the sections may be connected to each other to produce a unitary roadway.

A further object is to produce such a roadway section as may be quickly and easily 55 made longer or shorter.

Our invention comprises those novel parts and combinations thereof which are shown in the accompanying drawings, described in the specification and particularly defined by the claims terminating the same.

In the accompanying drawings we have shown our invention in a form which is now preferred by us, the same being illustrative of one manner in which the device may be made.

Figure 1 is a plan view of portions of several sections of roadway, showing a straightaway and a curve.

Figure 2 is a perspective illustrating the preferred manner of securing the roadway elements together.

The roadway is formed of short sections constructed in a manner to be later described more particularly, which may be secured together, and which may be taken up and laid down easily wherever it may be desired to locate a roadway. The individual sections are formed of beams 1 laid side by side, and connected by a flexible member, such as a cable 2. The various sections are secured in such manner that they may be attached together and detached quickly. The section is sufficiently flexible to ride over considerable inequalities in the surface and is broad enough so that it will not sink under a considerable load even in soft mud.

The individual sections are formed of a series of beams 1 laid side by side. These may be of a width only to support a single wheel, as illustrated by the sections 10, two such sections being laid side by side for the wheels at opposite sides of a vehicle, or the roadway elements may extend entirely across the width of the road to be laid, as illustrated by the sections 11. The shorter elements are adapted for use on straightaways, although it is evident that the longer elements may be used here if desired. These shorter elements will require less preliminary leveling prior to their laying than will longer elements, and they will be more flexible and conform more readily to the surface.

The longer elements, however, will provide a broader foundation, and are particularly desirable for use in curves, where the rear wheels of a truck, or the wheels of a trailer, will not track with the front wheels.

The beams 1 are secured together in some suitable manner as by a cable 2. As shown in Figure 2 the cable 2 passes through each

of the beams 1, through two spaced holes 12, preferably near the ends of the beam. The cable runs first through the holes 12 at one end of all the beams in a section and then 5 returns through the other series of holes. Its ends 20 are secured in some suitable manner. Other suitable means of securing the beams together, or of securing the cable thereto, may be employed without departing 10 from the scope of our invention. If it is desired to add more beams 1 this may be done by releasing the ends 20 of the cable, and threading on additional beams, splicing the ends of the cable if necessary. The sections 15 may be shortened in an analogous manner.

We prefer that the ends of the cable be not secured at the end of a section, but rather that they be secured at one of the intermediate beams. We prefer to secure them 20 in a peculiar manner, as illustrated in Figure 2, wherein each end 20 of the cable is passed through a single beam from opposite sides, and is then brought around to the outer end of the beam, where both ends are 25 secured under a single clamp 21 suitably secured to the end of the beam. The beam may be cut away as shown at 13 to permit manipulation of the ends 20.

At the ends of the sections we provide a 30 single beam 14 which is somewhat longer than the intermediate beams and which is bored to receive a bolt 15 by which adjoining sections may be clamped together. It may be found desirable, at the ends of the 35 sections, to join parallel sections by a connecting beam 16 extending between the two sections and clamped in place as by the bolts 15. Such connecting beams may be employed centrally of the sections if this is 40 found desirable, and but one such beam 16 need be employed where two sections are joined. Such connecting beams 16 are, of course, unnecessary in the sections 11 where the beams 1 extend entirely across the width 45 of the roadway, and where sections 10 are joined to sections 11.

It is evident that widely varying embodiments of our invention may be used without departing from the scope thereof. We do 50 not desire to limit ourselves to the construction described other than as limited by the appended claims.

What we claim as our invention is:

1. A portable sectional roadway, each sec-

tion consisting of a series of beams placed 55 side by side and a flexible cable passing through all said beams to hold them together.

2. A portable surfacing for roads composed of short sections each consisting of a series of beams placed side by side and having a hole passing through each near each end thereof, and a cable passing through the holes in one end of all the beams and back through the holes in the other end of all the 65 beams and with its ends relatively fixed.

3. A portable surfacing for roads composed of short sections each consisting of a series of beams placed side by side and having a hole passing through each near each 70 end thereof, and a cable passing through the holes in one end of all the beams and back through the holes in the other end of all the beams, said ends meeting away from the 75 ends of the section, and means for securing said ends to permit adjustment.

4. A portable surfacing for roads composed of short sections each consisting of a series of beams placed side by side and having a hole passing through each near each 80 end thereof, and a cable passing through the holes in one end of all the beams and back through the holes in the other end of all the beams, the ends of the cable meeting inward 85 from the ends of the section and both passing through one beam and brought to the outside and means for securing said ends.

5. A portable sectional roadway, each section consisting of a series of beams placed 90 side by side and a flexible cable passing through all said beams to hold them together, the end beams of each section being longer than the others to project their ends, and securing bolts passing through said 95 projecting ends to secure adjacent sections together.

6. A portable surfacing for roads composed of short sections each consisting of a series of beams placed side by side and each having two spaced holes therethrough, a cable passing through one hole of each beam and back through the other hole in all of the beams, and means for securing the ends of said cable.

Signed at Seattle, King County, Wash- 105 ington, this 17th day of December, 1920.

ARNOLD C. LUETGERT.

ERNEST H. MEIKLEJOHN.
